UNITED STATES PATENT OFFICE.

HATTIE PAULINE MERRICK, OF BROOKLINE, MASSACHUSETTS.

FOOT-COVERING.

1,009,772.

Specification of Letters Patent. Patented Nov. 28, 1911.

Application filed April 6, 1908. Serial No. 425,343.

To all whom it may concern:

Be it known that I, HATTIE PAULINE MERRICK, a citizen of the United States, residing in Brookline, county of Middlesex, 5 Commonwealth of Massachusetts, have invented certain new and useful Improvements in Foot-Coverings, of which the following is a specification, reference being had to the drawings which accompany the same.

10 My invention relates to a foot covering that may be made of paper, cloth or similar material, designed for more or less temporary use.

The object of my invention is to provide 15 a foot covering, inexpensive in construction, for use in cases of infectious or contagious diseases by physicians, nurses and others employed in the care of those having such diseases, to be worn as a foot covering while 20 they are in the presence of the sick persons, or in the house where such persons are located. The foot covering is to be removed and destroyed or sterilized or, leaving the rooms or the house where such persons are 25 located, thus to prevent the spread of the germs of contagious or infectious diseases.

In the drawings forming a part of this 30 specification—Figure 1 is a plan showing the form of the material from which my foot covering is made; Fig. 2 is an isometric elevation of my improved foot covering folded and fastened together ready for use.

In the drawings, 1 designates the body 35 part of material used in the manufacture of my improved foot covering, which material is preferably composed of a single piece cut out to the shape shown in Fig. 1.

When the foot covering is made of one 40 piece of material of the shape shown in Fig. 1, it has the portion 2 shaped to form the top of the toe of the covering when folded back on the dotted line 3. The sides 4 and 5 are folded inwardly on the dotted lines 6 and 7, preferably so that the portions 8 and 9 will overlap, as shown in Fig. 2. If 45 the foot covering is made of paper or other inexpensive material it may be made sufficiently strong to serve the purpose by overlapping the portions 8 and 9 and by fastening 50 them together and to the portion 2.

The heel part is formed from the two inner portions 10 and 11 by first folding them on the dotted lines 12 and 13 to stiffen the back of the heel, and then overlapping

and securing them together as shown in 55 Fig. 2. The folds and the overlapping portions may be secured together either by pasting, gluing, or by staples, rivets, or similar fastening devices.

For the purpose of illustration, I have 60 shown my improved foot covering as composed of a single piece of material so formed as to be folded to form a covering shaped similar to a slipper. The shape of the material and the method of folding may 65 be somewhat varied without departing from the spirit of my invention.

The purpose of my invention is to make 70 a foot covering that is comparatively inexpensive; that may be easily put on and taken off the feet; that is flexible and easily folded for transportation or to be carried by the person who is to use it; and that can be quickly burned or sterilized after it has 75 been used.

My improved foot covering is designed 80 for use in surgical cases, and in cases of contagious or infectious diseases, by surgeons, physicians, nurses or attendants, to prevent the carrying and spreading of the germs of 85 infectious or contagious diseases from the presence of those suffering from such diseases, and to prevent the carrying of germs into the surgical wards or operating rooms of hospitals and such institutions by the 90 feet of those having business within such places.

What I claim is—

A foot covering made of one piece of 90 flexible material cut to form the sole and sides of the foot covering and folded upwardly from the toe, the sides thereafter folded upwardly to lap over the toe-piece and each other at the toe and heel, and the folds secured together with fasteners at the 95 heel and the top of the toe, substantially as shown and described, the folds of the toe, heel and upper so overlapping as to leave no seams or openings near the sole part of the foot covering.

In testimony whereof, I have hereunto set my hand, in the presence of two subscribing witnesses, this the 23rd day of March, A. D. 1908.

HATTIE PAULINE MERRICK.

Witnesses:

A. H. SPENCER,
